UNITED STATES PATENT OFFICE

154,200

DESIGN FOR A CLOTHESPIN BAG OR SIMILAR ARTICLE

Pauline Gold, Hillside, N. J.

Application December 18, 1947, Serial No. 143,197

Term of patent 14 years

(Cl. D87—5)

To all whom it may concern:

Be it known that I, Pauline Gold, a citizen of the United States, residing in the township of Hillside, county of Union and State of New Jersey, have invented a new, original, and ornamental Design for a Clothes Pin Bag or Similar Article, of which the following is a specification, reference being had to the accompanying drawing, forming a part thereof:

I claim:

The ornamental design for a clothes pin bag or similar article, as shown.

PAULINE GOLD.
